Primary Examiner — Ricky Pham(74) *Attorney, Agent, or Firm* — Seed Intellectual Property Law Group LLP(57) **CLAIM**

The ornamental design for a popcorn popper, as shown and described.

DESCRIPTION

FIG. 1 is a top, front perspective view of a popcorn popper in a fully open configuration showing my new design.

FIG. 2 is a front elevation view thereof; the opposing rear view elevation is identical thereto.

FIG. 3 is a left side elevational view thereof; the opposing rights side elevation view is identical thereto.

FIG. 4 is a top plan view thereof.

FIG. 5 is a bottom plan view thereof.

FIG. 6 is a top plan view thereof with the lid partially closed; and,

FIG. 7 is a top plan view thereof with the lid fully closed.
